ATTORNEY

UNITED STATES PATENT OFFICE.

CLAUDE L. ABBOTT, OF GENOA, NEBRASKA.

MATCH HOLDER.

Application filed July 6, 1921. Serial No. 482,761.

To all whom it may concern:

Be it known that I, CLAUDE L. ABBOTT, a citizen of the United States, residing at Genoa, in the county of Nance and State 5 of Nebraska, have invented certain new and useful Improvements in Match Holders, of which the following is a specification.

This invention relates to a match box or holder, the general object of the invention 10 being to so construct the holder that matches will be discharged through an opening in the top thereof by pressing downwardly upon the holder.

Another object of the invention is to provide 15 a stationary bracket having guiding means thereon for the holder and a table or support located in the holder upon which the matches rest.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the 30 several views, and in which:—

Figure 1 is a perspective view of the device.

Figure 2 is a sectional view showing the same in filled position.

Figure 3 is a like view showing the same in unfilled position.

Figure 4 is a section taken at right angles to Figure 2.

Figure 5 is a perspective view of the 40 bracket and table.

Figure 6 is a rear perspective view of the housing.

In these views 1 indicates a bracket which is adapted to be secured by screws or the 45 like to a wall 2 or other support. A table 3 extends at right angles from the bracket and is connected to the bracket by the neck 4. A guiding ear 5 extends outwardly from each side of the bracket adjacent its 50 upper end.

The housing 6 has a cross sectional shape to snugly receive the table so that the housing can slide thereon, the rear of the housing having a longitudinally extending slot 7

through which the neck 4 passes. The sides 55 of the housing, at the rear thereof, engage the guides 5 so that the housing is guided in its vertical movement. The upper end of the housing is of wedge-shape, as shown at 8, and has an opening 9 at the upper end 60 of this wedge-shaped part through which the matches are adapted to be discharged.

As will be seen in Figure 3 when the housing is empty of matches it will be in its lowest position with the table engaging the 65 reduced upper end thereof but when the housing is filled or partly filled with matches the said matches will support the housing in its raised position from the table and when it is desired to remove some of 70 the matches it is simply necessary to press upon the sloping faces of the top of the housing with the thumb and first two fingers to force the housing downwardly and thus cause some of the matches to be discharged 75 through the opening 9.

The housing can be filled by dropping the matches through the opening 9 or it can be filled through the open bottom of the housing and then the housing can be placed 80 over the table so that the matches will be supported by said table.

It is thought from the foregoing description that the advantages and novel features of my invention will be readily apparent. 85

I desire it to be understood that I may make changes in the construction and in the combination and arrangement of the several parts, provided that such changes fall within the scope of the appended claims. 90

What I claim is:—

1. A match holder of the class described comprising a supporting bracket, a table having a neck connected with the bracket, a housing enclosing the table and having a 95 slot therein for receiving the neck and a discharge opening in the top of the housing.

2. A match holder of the class described comprising a supporting bracket, a table having a neck connected with the bracket, 100 a housing enclosing the table and having a longitudinally extending slot for receiving the neck, said housing having a wedge shaped top having a discharge opening therein and guiding ears on the bracket engaging the housing. 105

In testimony whereof I affix my signature.

CLAUDE L. ABBOTT.
